UNITED STATES PATENT OFFICE

2,684,782

CUBE SUGAR DISPENSER

Ermal J. Lime and Charles S. Hedges, Kansas City, Mo., assignors to Crelo Manufacturing Company, Inc., Kansas City, Mo., a corporation of Missouri

Application March 1, 1952, Serial No. 274,396

4 Claims. (Cl. 221—174)

1

This invention relates to dispensing apparatus and more particularly to apparatus for dispensing cube sugar for use in connection with beverage vending machines and the like.

In machines for vending beverages such as coffee and the like it is desirable to have a selective arrangement for adding sugar to the beverage to suit the taste of the purchaser. While it is desirable to have the sugar dispenser arranged and operated relative to the beverage vending machine where the purchaser at his own election can have his beverage without sugar, or with one or two cubes of sugar, it is also desirable that the total number of cubes available for any one container or cup of beverage be limited to prevent the cost of the cup of beverage being excessive and also to prevent emptying of the sugar dispenser by the purchase of one cup of beverage.

The objects of the present invention are to provide a cube sugar dispenser with a discharge port and selectively operated mechanism for controlling said port for delivery of one cube of sugar at a time; to provide such a dispenser with a movable member having a plurality of pockets which is operated to move cubes of sugar into alignment with the discharge port, said movable member being actuated only at each time a cup of beverage is purchased; to provide a cube container arranged to support the weight of the principal portion of the cubes and limit the quantity affected by the movable member; to provide a cube lifting member moved with the movable member to eliminate bridging of the cube sugar in the container; to provide a sugar dispenser with a discharge chamber separated from the main body of sugar in the dispenser and having such communication therewith as to limit the quantity of sugar cubes in the discharge chamber; and to provide a cube sugar dispenser which is economical to manufacture, efficient in operation and easily serviced.

In accomplishing these and other objects of the present invention, we have provided improved details of structure, the preferred forms of which are illustrated in the accompanying drawings, wherein:

Fig. 1 is a perspective view of a cube sugar dispenser embodying the features of the present invention.

Fig. 2 is a vertical sectional view through the cube sugar dispenser on the line 2—2, Fig. 3.

Fig. 3 is a transverse sectional view through the dispenser on the line 3—3, Fig. 2.

Fig. 4 is a transverse sectional view showing the dispenser operating mechanism from the line 4—4, Fig. 2.

2

Fig. 5 is a vertical sectional view through the lower portion of the dispenser with the control mechanism operated for the discharge of one cube of sugar.

Fig. 6 is an elevational view of the lower portion of the dispensing apparatus.

Fig. 7 is a diagrammatic view of the electrical circuits for the cube sugar dispenser.

Referring more in detail to the drawings:

10 1 designates a cube sugar dispensing apparatus adapted to be used with a machine (not shown) for vending beverages by the cup or like container. The cube sugar dispensing apparatus preferably consists of a container 2 having cylindrical, vertically arranged walls 3, the lower end of which is suitably secured to a bottom member 4, illustrated as being rectangular in shape and having depending legs 5 with feet 6 on the lower ends thereof adapted to be mounted on a suitable support to space the bottom 4 above said support sufficiently for operating mechanism located therebetween as later described.

20 A suitable cover 7 is removably mounted on the upper end of the walls 3 to close the upper end of the container, the cover 7 being removable for servicing of the dispenser by the addition of cubes of sugar to the container.

25 A funnel-shaped partition 8 is suitably arranged in the container, in spaced relation to the bottom 4, to define a discharge chamber 9 between the partition and the bottom and a storage chamber 10 above the partition. The funnel-shaped partition preferably has a suitable portion such as a cylindrical, vertical wall 11 slidably engaging the interior of the container wall 3, the lower end of said vertical wall 11 terminating in a downwardly and inwardly sloping wall 12 of substantially conical formation, said wall 12 having a central, axial aperture 13 therein for passage of cubes of sugar from the storage chamber 10 to the discharge chamber 9 as later described.

30 The partition 8 preferably rests on a rib or the like 14 extending inwardly from the container wall 3 and spaced from the bottom 4 to limit the height of the discharge chamber 9 for movement of cubes of sugar therethrough to a discharge port 15 in the bottom 4 of the container, said discharge port preferably being adjacent the side wall 3 as illustrated in Figs. 2 and 5. A shaft 16 is rotatably mounted in an axial bore 17 in the bottom 4. The lower end of the shaft extends below the bottom 4 and secured to the lower end of the shaft is a coupling 18 operatively connecting the shaft 16 with a shaft 20 driven by a motor 21. The motor 21 is preferably of the type having a gear reduction unit enclosed in a portion 22 of

the motor housing whereby the shaft 16 is driven at a relatively slow speed. The motor and gear reduction are secured by suitable fastening devices 23 to a bar 24 of a U-shaped bracket 25 having the upper ends of vertically extending legs 26 suitably secured as at 27 to the bottom 4, wherein the bar portion 24 of the bracket is spaced below the bottom 4. A cam member 28 is rigidly secured to the shaft 16 between the upper end of the coupling 18 and the bottom 4, said cam having lobes 29 and dwells 30 in its periphery for opening and closing a microswitch 31 supported on a bracket 32 in such a manner that a roller 33 on the arm 34 of the switch engages the periphery of the cam, the microswitch 31 being connected into the circuit of the motor 21 for controlling operation of same as later described. The upper end of the shaft 16 extends axially of the container 2 through the discharge chamber and for a substantial distance into the storage chamber 10 illustrated in Fig. 2.

A rotor 35 is arranged in the discharge chamber 9 and secured to the shaft 16 by a key 36. The bottom of the rotor has a flat surface 37 which is spaced from the upper surface 38 of the bottom 4 by means of suitable washers or the like 39. The upper portion of the rotor, as illustrated in Figs. 2 and 5, has a flat portion 40 adjacent the shaft 16, said flat portion terminating in a downwardly and outwardly sloping substantially conical surface 41, which terminates in a flat portion 42 that extends to the periphery of the rotor. The thickness of the rotor between the bottom surface 37 and the surface 42 is preferably slightly greater than the thickness of one or more cubes of sugar as desired. The rotor 35 is provided with a plurality of pockets 43 equally spaced around the periphery of the rotor. Each of the pockets extends vertically through the rotor and is of sufficient width and radial depth for free movement of one cube of sugar through the pocket. A lifting device in the form of a coil spring 44 or the like is sleeved on the shaft 16 and extends from the flat surface 40 of the rotor to the upper end of the shaft, said spring being held on the shaft by means of a cap 45 secured as by a screw 46 to the upper end of the shaft. The shaft 16 and spring 44 thereon are of such size relative to the aperture 13 through which they extend that cubes of sugar will pass between the edge of the aperture and the spring.

Cubes of sugar contained in the storage chamber 10 are supported on the conical wall 12 of the funnel member 8, and while cubes can pass through the space between the edges of the aperture 13 and the spring 44, there is a natural tendency for the cubes to bridge the aperture so that no cubes would fall through the aperture. Also the spacing of the top of the rotor from the edge of the aperture 13 is such that the cubes of sugar tend to arrange themselves in one layer on the upper surface of the rotor and slide into the pockets 43 and not permit additional cubes to flow out over the first layer on the rotor and stack up on the discharge chamber.

Operation of the motor 21 rotates the shaft 16 and the rotor 35 to align one of the pockets 43 with the discharge opening 15. The next operation of the motor again turns the shaft and rotor to move another pocket 43 into alignment with the discharge opening 15. In the illustrated structure, there are four pockets on the rotor whereby the shaft 16 and rotor 35 are turned one-quarter of a revolution on each operation of the motor 21. This rotation of the shaft 16 also

turns the spring 44 which is coiled in such a manner that the rotation provides a lifting action on the cubes of sugar bearing thereagainst, thereby providing slight agitation of the cubes in the storage chamber 10 to prevent any bridging action, thereby causing the cubes to move through the aperture 13.

Discharge of cubes of sugar through the discharge port 15 is controlled by a slide 47, having an opening 48 which through operation of the slide is moved into and out of registry with the discharge port 15. The slide 47 is preferably arranged diametrically of the container adjacent the lower face of the bottom 4. The portion of the slide adjacent the opening 48 is slidably supported on a U-shaped guide 49 secured by suitable fastening devices 50 to the bottom 4. The end of the slide remote from the opening 48 is offset as at 51 and connected to the armature 52 of a solenoid 53 which is suitably supported on the bottom 4. The intermediate portion of the slide is provided with an elongated opening 54 through which the shaft 16 extends. The ends of the opening may engage the shaft 16 to limit the extent of movement of the slide. A spring 55 has one end connected to the slide adjacent the offset portion 51 and the other end connected to the shaft 16 to resiliently urge the slide away from the solenoid, the elongated opening 54 and discharge opening 48 being so arranged that when the solenoid is energized the slide will be drawn toward the solenoid to effect registry of the opening 48 with the discharge portion 15, and when the solenoid is deenergized the spring 55 moves the slide to the other end of its stroke wherein the opening 48 is out of registry with the discharge port 15 as shown in Fig. 2.

A vane 56 is secured to the slide 47 between the opening 48 and elongated opening 54. The vane extends through a slot 57 in the bottom 4 and lies on the upper surface thereof and covers the discharge port 15 when the opening 48 is out of registry therewith and is moved to uncover the discharge port 15 when the opening 48 is in registry with said port. The vane prevents cubes of sugar from engaging the edges of the discharge port when the rotor 35 is rotated. This arrangement, together with the thickness of the rotor, prevents broken cubes or pieces from interfering with the operation of the apparatus.

In the illustrated structure, the bottom 4 is provided with a slotted portion 57 in alignment with the slide and serving as a guide for stop member 57' on an inwardly directed vane 53 which extends through a slot 58 in the wall 3 of the container. The vane 53 is secured to the lower end of a flat spring 60 as at 61, the upper end of said spring being secured as by suitable fastening devices 62 to the exterior of the container side wall 3 in vertical alignment with the vane 53. The flat spring urges the vane toward and into the slot 58 and the stop member into engagement with the end of the slide adjacent the opening 48. The engagement of the stop member and slide is such that movement of the slide moves the vane in the same direction. The inner end of the vane is arranged relative to the opening 48 of the slide whereby when said slide is moved to position the opening in registry with the discharge port 15 the vane 53 extends into the discharge chamber to engage a cube of sugar in the pocket 43 that is aligned with the discharge port and is above the cube on the vane 56 ready for discharge. When the slide is moved

wherein the opening 48 is out of registry with the discharge port 15, the engagement of the slide and stop member swings the vane outwardly on the spring relative to the container whereby the next cube of sugar in the pocket 43 may drop down onto the vane 56 as illustrated in Fig. 2.

In using a sugar dispenser constructed as described in connection with a beverage vending machine, the motor 21 is connected to a suitable source of electrical energy with the microswitch 31 in one of the leads to the motor, said lead being in parallel circuit with the control circuit of the vending machine in such a manner that when a coin is placed in the vending machine and the electrical apparatus thereof energized a relay 62 is energized to close the circuit to the motor 21 to start same operating, the time element of the energization of the vending machine circuit being such that the motor will operate from such circuit sufficiently to rotate the cam 23 until the roller 33 moves off of a lobe of the cam, whereby the arm 34 will close the switch 31. The motor 21 will then be energized independently of the vending machine to continue operation until the next lobe 29 is engaged with the roller 33 to lift the arm 34 and disengage the contacts of the switch 31, breaking the circuit to the motor 21. There are the same number of lobes 29 on the cam 23 as there are pockets 43 in the rotor and the lobes of the cam are positioned relative to the pockets 43 whereby when the motor 21 is de-energized, one of the pockets 43 will be in alignment with the discharge port 15. Also rotation of the shaft 16 by the motor 21 prevents bridging of the cubes of sugar whereby said cubes will pass into the discharge chamber and over the upper face of the rotor into the pockets 43. Due to the vane 56 covering the discharge port 15, the thickness of the rotor, the slope of the upper surface of the rotor, and spacing between the rotor and the partition, no more than a desired number of cubes of sugar will become aligned with the discharge port 15, and the interengagement of the cubes on the upper surface of the rotor is such that additional cubes of sugar will not slide into the pocket 43 when the rotor is stationary.

If the purchaser desires no sugar, the cubes remain undisturbed until the vending machine is again operated to obtain a cup of beverage, at which time the motor 21 is again energized to rotate the rotor and position the next pocket 43 in alignment with the discharge port 15, the cubes of sugar moving onto the vane 56 which has thin edges to facilitate such movement without damage of cubes. If the purchaser desires sugar he presses a manual switch 64 in a circuit connecting the solenoid with the source of suitable current to energize said solenoid to move the slide and vane 56 to effect registry of the discharge opening 48 with the discharge port 15 and uncover said port. Simultaneously with such movement, the vane 58 enters the discharge chamber to engage and support the next cube of sugar in the pocket 43 above the one in the discharge port, which will drop through the discharge opening 48 into a chute 65 and slide therethrough to drop in a cup of beverage. Upon release of the switch a spring 55 will return the slide to move the vane 56 into covering relation with the discharge port 15 and the opening 48 out of registry with the discharge port 15 and through engagement of the end of the slide and stop member 57 the vane 58 is also moved outwardly sufficiently to allow the next cube of sugar to drop onto the vane 56. If the purchaser

desires a second cube of sugar he can again close the switch 64, energize the solenoid and repeat the process. Since only a desired number of cubes can be stacked in registry with a pocket 43, the purchaser will be limited to that number of cubes, although he can continue to operate the switch to energize the solenoid and effect reciprocation of the slide.

It is believed obvious that we have provided a dispenser for cube sugar for positive and efficient dispensing of a limited number of cubes into cups or other containers of beverage.

What we claim and desire to secure by Letters Patent is:

- 15 1. Apparatus for dispensing one or more of a limited quantity of cubes of sugar and the like comprising, a container having a bottom and upwardly extending cylindrical side wall thereon, a cover removably mounted on the upper end 20 of the side wall to close the container, said container having a discharge port in the bottom adjacent the side wall, a funnel-shaped partition having a periphery engaging the side wall of the container, means in the container supporting the 25 partition in spaced relation to the bottom for defining a cube storage chamber above the partition and a discharge chamber below the partition, said partition having an aperture therein for passage of cubes into the discharge chamber, 30 a rotor in the discharge chamber having a plurality of spaced pockets in the periphery thereof, said rotor adjacent the pockets being of a thickness substantially corresponding to the collective thickness of a desired maximum quantity 35 of cubes to be dispensed from any one position of the rotor, means for rotating said rotor to position the respective pockets in registry with the discharge port, said rotor having a sloping upper surface suitably spaced from the partition 40 whereby rotation of the rotor effects movement of cubes over said upper surface into the pockets, a slide member normally closing the discharge port and movable to open same for dispensing cubes through said discharge port from the respective pocket in registry therewith, and means 45 operable by the slide member to extend into the respective rotor pocket above the discharge port as the slide is moved to open the discharge port for supporting any cubes above the one adjacent to and aligned with the discharge port whereby 50 the cubes are dispensed one for each time the slide member is moved to open the discharge port until the respective registering rotor pocket is empty.

- 55 2. Apparatus for dispensing one or more of a limited quantity of cubes of sugar and the like comprising, a container having a bottom and upwardly extending cylindrical side wall thereon, a cover removably mounted on the upper end 60 of the side wall to close the container, said container having a discharge port in the bottom adjacent the side wall, a funnel-shaped partition having a periphery engaging the side wall of the container, means in the container supporting the partition in spaced relation to the bottom for defining a cube storage chamber above the partition and a discharge chamber below the partition, said partition having an aperture therein for passage of cubes into the discharge chamber, 65 a rotor in the discharge chamber having a plurality of spaced pockets in the periphery thereof, said rotor adjacent the pockets being of a thickness substantially corresponding to the collective thickness of a desired maximum quantity 70 of cubes to be dispensed from any one position of the rotor, means for periodically rotating said

rotor to position the respective pockets in registry with the discharge port, said rotor having a sloping upper surface suitably spaced from the partition whereby rotation of the rotor effects movement of cubes over said upper surface into the pockets, a slide member movably supported on the bottom and having an opening therein normally out of registry with the discharge port and movable into registry therewith for dispensing cubes through said discharge port from the respective pocket in registry therewith, means operable by the slide member and movable into the respective rotor pocket above the discharge port as the opening in the slide is moved to effect registry thereof with the discharge port for supporting any cubes above the one adjacent to and aligned with the discharge port whereby the cubes are dispensed one for each time the opening in the slide member is moved into registry with the discharge port until the respective registering pocket of the rotor is empty, and resilient means acting on the slide member for urging said slide member into discharge port closing position.

3. Apparatus for dispensing one or more of a limited quantity of cubes of sugar and the like comprising, a container having a bottom and upwardly extending cylindrical side wall thereon, a cover removably mounted on the upper end of the side wall to close the container, said container having a discharge port in the bottom adjacent the side wall, a partition in the container having a downwardly and inwardly sloping wall and an axially arranged aperture therein, the periphery of the partition engaging the side wall of the container, means in the container supporting the partition in spaced relation to the bottom for defining a cube storage chamber above the partition and a discharge chamber below the partition, a rotor in the discharge chamber having a plurality of spaced pockets in the periphery thereof, said rotor adjacent the periphery thereof being of a thickness substantially corresponding to the collective thickness of a limited maximum quantity of cubes to be dispensed from any one position of the rotor, power means for rotating said rotor to position the respective pockets in registry with the discharge port, said rotor having a sloping upper surface suitably spaced from the partition whereby rotation of the rotor effects movement of cubes over said upper surface into the pockets, a coil member extending upwardly from the rotor through the partition aperture and into the storage chamber and rotatable with the rotor to lift and agitate the cubes in the storage chamber and facilitate feed thereof to the discharge chamber, a slide member movably mounted adjacent the bottom of the container and having an opening therein normally out of registry with the discharge port, means operatively connected with the slide member for moving same to effect registry of the opening therein with the discharge port for dispensing cubes through said discharge port from the respective pocket in registry therewith, resilient means acting on the slide member for urging same into discharge port closing position, a flat spring having one end secured to the container and the other end adjacent the slide, and a vane supported on said other end of the flat spring and spaced above the slide and having a portion engaging the slide member for movement of said vane into the respective rotor pocket above the discharge port as the opening in the slide is moved to effect registry thereof

with the discharge port for engaging any cube above the one adjacent to and aligned with the discharge port.

4. Apparatus for dispensing one or more of a limited quantity of cubes of sugar and the like comprising, a container having a bottom and upwardly extending cylindrical side wall thereon, a cover removably mounted on the upper end of the side wall to close the container, said container having a discharge port in the bottom adjacent the side wall, a partition in the container having a downwardly and inwardly sloping wall and an axially arranged aperture therein, an upwardly extending cylindrical wall on the periphery of the partition slidably engaging the side wall of the container, means in the container supporting the partition in spaced relation to the bottom for defining a cube storage chamber above the partition and a discharge chamber below the partition, a rotor in the discharge chamber having a plurality of spaced pockets in the periphery thereof, said rotor adjacent the pockets being of a thickness substantially corresponding to the collective thickness of a desired maximum quantity of cubes to be dispensed from any one position of the rotor, power means for rotating said rotor to position the respective pockets in registry with the discharge port, said rotor having a sloping upper surface suitably spaced from the partition whereby rotation of the rotor effects movement of cubes over said upper surface into the pockets, a coil member extending upwardly from the rotor through the partition aperture and into the storage chamber and rotatable with the rotor to lift and agitate the cubes in the storage chamber and facilitate feed thereof to the discharge chamber, a slide member movably mounted adjacent the bottom of the container and having an opening therein normally out of registry with the discharge port, means operatively connected with the slide member for moving said slide member to effect registry of the opening therein with the discharge port for dispensing cubes through said discharge port from the respective pocket in registry therewith, resilient means acting on and urging the slide member into discharge port closing position, a flat resilient member aligned with the slide member and extending upwardly alongside the container, means connecting the upper portion of the flat resilient member to the container wall whereby the lower portion is movable toward and away from the container, a vane secured to the lower end of the resilient member and spaced above the slide at least the thickness of one cube, and means on the vane engaging the slide whereby said vane is movable with the slide and when the slide is moved to effect registry of the opening thereof with the discharge port the vane moves into the respective rotor pocket and engages any cubes above the one adjacent to and aligned with the discharge port whereby the cubes are dispensed one for each time the opening in the slide member is moved into registry with the discharge port until the respective registering pocket of the rotor is empty.
